UNITED STATES PATENT OFFICE.

GUSTAVUS W. JEWELL AND ROBERT M. DICKSON, OF EARL PARK, INDIANA.

CHECK-ROWER FOR CORN-PLANTERS.

SPECIFICATION forming part of Letters Patent No. 335,361, dated February 2, 1886.

Application filed September 12, 1885. Serial No. 176,952. (No model.)

To all whom it may concern:

Be it known that we, GUSTAVUS W. JEWELL and ROBERT M. DICKSON, of Earl Park, in the county of Benton and State of Indiana, have invented a new and useful Improvement 5 in Check-Rowers for Corn-Planters, which improvement is fully set forth in the following specification and accompanying drawings, in which—

10 Figure 1 is a plan view of our check-rower for corn-planters; Fig. 2, a longitudinal central section of the same; Fig. 3, a perspective view of the feed-bar attachment detached; Fig. 4, a plan view of the cam detached, and 15 Fig. 5 a diagram showing the movement of the trailing wheel.

The present invention relates to an improved check-rower for corn-planters, wherein we provide colter-wheels which cut through the clods 20 and upper surface of the soil, so as to permit the measuring to be done more equally than if the wheel had a broad tire; and also in having a cam consisting of two members on the axle-shaft, and engaging therewith a pair of 25 friction rollers and levers so disposed as to operate above the feed-bar and rearwardly a trailing wheel, so that a mark may be made centrally between the rows corresponding with the space of the hills, all of which will now be 30 set forth in detail.

In the accompanying drawings, A represents the frame-work of an ordinary corn-planter and check-rower; B, the axle, and C the pole.

In place of the ordinary felly-wheel to attach to the axle B, we provide colter-wheels 35 D, formed of a metallic disk with a sharp cutting-edge, E, or, what might occasionally be preferred, constructed as an ordinary spoke-wheel, but having the felly formed of a flat 40 metal rim set on a plane corresponding with the spoke.

Inwardly each end of the frame A is provided with the planter-shoes F. Above this frame the usual feed-bar, G, is provided.

45 Upon the rotating axle-shaft B we provide a cam, H, formed in two sections or members, with somewhat of a space between them, and adjustable upon the said axle-shaft by means of set-screws I. The inner face of these members has a raised shoulder, H', extending 50 around nearly one-half of the face, while the opposite member has also a corresponding

raised surface, so that when placed opposite each other, as shown in Fig. 4, the friction-roller placed therein and attached to the lever will have a reciprocal motion when the shaft 55 B is rotated. Rearwardly from this cam H we provide a vertical metallic support, J, secured to the frame A by means of the forwardly-projecting wings L and M at the upper and 60 lower part of this piece. The upper wing, L, has a lever, N, journaled thereon and projecting slightly forward, with the friction-wheel O journaled vertically thereto and resting within the recess between the two members of 65 the cam H, while at the same time the opposite end of the lever N projects rearwardly and operates within a vertical keeper, P, of an adjustable attachment, Q, on the feed-bar G. The lower wing, M, of the support J has also 70 a lever, R, the forward end provided with a friction-roller, S, also resting within the spaces between the members of the cam-wheel H. This lever also projects rearwardly some distance and connects by means of a cross-bar, 75 T, with a bar, U, parallel with the said lever R, and hinged forwardly to the under face of the frame A, and carrying a trailing wheel, V, centrally beneath the device.

Immediately forward of the trailing wheel 80 V, I provide a rearwardly-projecting arm, X, hinged to the frame A, having rearwardly a transverse scraper, Y, so that the clods may be removed and thus leave a level surface for the trailing wheel V to do its work more perfectly. 85 As the device moves forward, the rotation of the axle-shaft B, engaging with the roller O, operates the lever N in one direction, while the lower lever, R, having forwardly the friction-roller S, also engaging with the said cam, 90 operates in the opposite direction. This upper lever, N, thus operates the feed-bar G, extending into the seed-boxes over the planter-shoes F, (not shown in the drawings,) and the lower lever, R, having lateral motion rear- 95 wardly, causes the trailing wheel V to act as a marker, as shown in the plan, Fig. 5, by the dotted lines W. This trailing wheel V is thus diverted laterally at regular intervals, so as to correspond with the location of the hill.

The colter-wheel D is arranged so as to be used for cutting through the clods and upper surface of the soil, and thus permit the measuring to be done more equally than if the wheel

had a broad tread, and thus moved over the top of the clods and uneven surface of the ground.

Having thus described our invention, what we claim as new is—

- 5 1. The combination in a check-rower for corn-planters, of a pair of levers, one connecting with the feed-bar and the other with the trailing wheel, with a swivel cam-wheel on the axle-shaft whereby one lever operates the feed-bar while the other diverts the trailing wheel to form a mark diverted laterally at regular intervals.
- 10 2. The combination of the frame A, the wings L and M, carrying thereon the levers N and R, the keeper P, the feed-bar attachment Q, the trailing wheel V, and leveling-scraper Y, substantially as herein described.

3. The combination of the frame A, the pole C, the axle B, and the colter-wheels E, with the feed-bar G, the cam H, the friction-rollers 20 O and S, the levers N and R, the trailing wheel V, and the scraper Y, the whole arranged and operated substantially as herein described and set forth.

In testimony that we claim the foregoing 25 we have hereunto set our hands, this 27th day of August, 1885, in the presence of witnesses.

GUSTAVUS W. JEWELL.
ROBERT M. DICKSON.
